UNITED STATES PATENT OFFICE

LEON A. DOUGHTY, OF GLENSIDE, PENNSYLVANIA

DESIGN FOR A STORAGE BATTERY BOX

Application filed January 31, 1933. Serial No. 47,064. Term of patent 14 years.

To all whom it may concern:

Be it known that I, LEON A. DOUGHTY, a citizen of the United States, and a resident of Glenside, county of Montgomery, State of Pennsylvania, have invented a new, original, and ornamental Design for Storage Battery Box, of which the following is a specification, reference being had to the accompanying drawing, forming a part thereof.

The figure represents a perspective of a storage battery box showing my new design. I claim:—

The ornamental design for a storage battery box substantially as shown.

LEON A. DOUGHTY.
